UNITED STATES PATENT OFFICE.

THOMAS SEEVERS, OF OSKALOOSA, IOWA.

BOILER.

SPECIFICATION forming part of Letters Patent No. 340,827, dated April 27, 1886.

Application filed January 8, 1886. Serial No. 188,012. (No model.)

To all whom it may concern:

Be it known that I, THOMAS SEEVERS, a citizen of the United States, residing at Oskaloosa, in the county of Mahaska and State of Iowa, have invented a new and useful Improvement in Boilers, of which the following is a specification, reference being had to the accompanying drawings.

My invention relates to an improvement in base-burning magazine steam-boilers; and it consists in the peculiar construction and combination of devices, that will be more fully set forth hereinafter, and particularly pointed out in the claim.

15 In the drawings, Figure 1 is a vertical central sectional view of my invention. Fig. 2 is a similar view of the same, taken on a plane at right angles to Fig. 1. Fig. 3 is a horizontal section taken on the line *xx* of Fig. 1. 20 Fig. 4 is an elevation of a boiler, the inclosing brick-work being omitted.

25 A represents the cylindrical outer shell of the boiler, and B represents a steam-dome, which is of less diameter than the boiler, and is located on the upper end thereof.

30 C represents the fuel-magazine, which is located centrally in the outer shell, and is shaped like the section of a cone, the lower end of the magazine being larger than the upper end thereof. The crown-sheet D of the magazine is connected to the upper side of the steam-dome by means of a rod, E, and clamping-nuts, which are screwed onto the upper and lower ends of the said rod.

35 F represents the fire-box at the lower end of the magazine, and also located centrally in the shell A, at the lower end thereof. This fire-box is of greater diameter than the lower end of the magazine, and the walls of the said 40 fire-box are inclined and converge toward the lower end thereof, the said fire-box being thus made smaller at its lower end than at its upper end. A coal-chute, G, communicates, near the upper end of the magazine, on the 45 front side thereof, with the outer shell of boiler A, and to the outer end of this chute is hinged a door, H.

I represents a series of smoke-flues, which connect the upper side of the fire-box and the 50 upper end of the boiler, around the magazine, the said flues almost entirely surrounding the

magazine. By this construction a space, Z, is left in the boiler, which entirely surrounds the fire-box and the magazine, so as to bring the water in direct contact with the heated 55 parts of the furnace, and through this water-space pass the heated flues, whereby steam may be generated very rapidly and with a minimum consumption of fuel.

A door, K, communicates with the fire-box, 60 and the said fire-box is provided with the shaking-grate L. A lever, M, is fulcrumed on the outer side of the furnace, and is connected to the grate L, by which means the grate may be shaken, so as to agitate the burning coal. An ash-pit, M', is formed below the fire-box, and is provided with a door, N, which door regulates the draft.

The boiler is incased in brick-work, O, as shown in Figs. 1, 2, and 3, and the said brick-work is formed with a flue, P, which surrounds the boiler, has a chimney, R, and is provided with suitable openings and doors, by means of which the soot may be removed and access gained to the lower end of the boiler, 75 in order to remove the sediment therefrom through the man-holes S.

T represents a horizontal iron partition-plate, which is secured to the upper end of the boiler, and divides the flue P into an upper chamber, V, and a lower chamber, W. This partition-plate is cut away at its front 80 side, to form openings Y, communicating with the chambers V and W.

To the steam-dome is secured a pipe, a, 85 which communicates at its outer end with a pressure-valve, b, which is adapted to raise and lower a weighted lever, c, similarly to the ordinary safety-valve. The short end of the lever c is connected to the free lower side 90 of the door N by means of the chain d. When the pressure of the steam becomes too great for safety, the outer end of the lever c is raised, which causes the short end thereof to lower, and thereby close the door N and cut off the 95 draft to the fire. As the pressure of steam is decreased, the short end of the lever c rises, and thereby opens the door N to admit air to the fire, thus regulating the draft automatically.

The smoke and products of combustion pass 100 upwardly from the fire-box through the flues

I into the chamber or flue V, which surrounds the steam-dome, so as to superheat the steam therein, and from thence through the openings Y down into the flue or chamber W, and from thence up through the chimney.

Having described my invention, I claim—

The boiler comprising the vertical shell A, the steam-dome, of less diameter, on the upper end thereof, the magazine and fire-box located in the boiler, the said magazine being largest at its lower end, and the said fire-box being largest at its upper end, the flues I from the fire-box and extending through the upper end of the boiler, and the casing O, surrounding the boiler and having the upper chamber,

V, surrounding the steam-dome and the upper end of the boiler, and with which the flues I communicate, and the lower chamber, W, surrounding the lower portion of the boiler and communicating with the upper chamber, 20 V, for the purpose set forth, substantially as described.

In testimony that I claim the foregoing as my own I have hereto affixed my signature in presence of two witnesses.

THOMAS SEEVERS.
